TANDEM WALKER

John Q. Jackson, 2710 S. Normandie, Los Angeles, Calif.

Filed May 18, 1960, Ser. No. 60,630

Term of patent 7 years

(Cl. D7—7)

FIG. 1.

FIG. 2.

FIG. 3.

FIG. 5.

FIG. 4.

FIGURE 1 is a top plan view of a tandem walker illustrating my new design;

FIGURE 2 is a side view of the tandem walker shown in FIGURE 1;

FIGURE 3 is a bottom plan view of the walker shown in FIGURE 2;

FIGURE 4 is a front view of the walker shown in FIGURE 2; and,

FIGURE 5 is a rear view of the walker shown in FIGURE 2.

The dominant features of my design reside in the portions shown in full lines.

I claim:

The ornamental design for a tandem walker, substantially as shown and described.
